US0D1081794S

(12) **United States Design Patent** (10) **Patent No.:** **US D1,081,794 S**
(45) **Date of Patent:** **** Jul. 1, 2025**

(54) **ELECTRONIC SHELF LABEL**

(71) Applicant: **Hanshow Technology Co., Ltd.**
Zhejiang (CN)

(72) Inventors: **Peixuan Liu**, Zhejiang (CN); **Linjiang Wang**, Zhejiang (CN); **Xubing Du**, Zhejiang (CN); **Shiguo Hou**, Zhejiang (CN); **Jianguo Zhao**, Zhejiang (CN); **Ming Shen**, Zhejiang (CN)

(**) Term: **15 Years**

(21) Appl. No.: **35/524,579**

(22) Filed: **Mar. 7, 2025**

(80) **Hague Agreement Data**

Int. Filing Date: **Mar. 7, 2025**

Int. Reg. No.: **DM/245166**

Int. Reg. Date: **Mar. 7, 2025**

Int. Reg. Pub. Date: **Apr. 4, 2025**

(30) **Foreign Application Priority Data**

Sep. 13, 2024 (CN) 202430587394.X

Primary Examiner — Catherine Ho

(57) **CLAIM**

The ornamental design for an electronic shelf label as shown and described.

DESCRIPTION

1. Electronic shelf label

1.1 : Front

1.2 : Back

1.3 : Left

1.4 : Right

1.5 : Top

1.6 : Bottom

(Continued)

1.7 : Front perspective

1.8 : Back perspective

Purpose of the design product: the intended use of the electronic shelf label is for displaying information such as product name and price.

1 Claim, 8 Drawing Sheets
